(57) **CLAIM**

We claim the ornamental design for a light stand, as shown and described.

DESCRIPTION

FIG. 1 is a perspective view of a light stand in a stowed configuration embodying the invention.

FIG. 2 is a first side view of the light stand of FIG. 1.

FIG. 3 is a second side view of the light stand of FIG. 1.

FIG. 4 is a front view of the light stand of FIG. 1.

FIG. 5 is a rear view of the light stand of FIG. 1.

FIG. 6 is a top view of the light stand of FIG. 1.

FIG. 7 is a bottom view of the light stand of FIG. 1.

FIG. 8 is a perspective view of the light stand in a deployed configuration embodying the invention.

FIG. 9 is a first side view of the light stand of FIG. 8.

FIG. 10 is a second side view of the light stand of FIG. 8.

FIG. 11 is a front view of the light stand of FIG. 8.

FIG. 12 is a rear view of the light stand of FIG. 8.

FIG. 13 is a top view of the light stand of FIG. 8; and,

FIG. 14 is a bottom view of the light stand of FIG. 8.

(Continued)

Portions of the light stand shown in broken lines are for illustrative purposes only and form no part of the claimed design.

1 Claim, 9 Drawing Sheets
